SHUTTLE PICKING MECHANISM

Albert Moessinger, Zurich, Switzerland, assignor
to Sulzer Freres Societe Anonyme, Winterthur,
Switzerland

Application February 9, 1937, Serial No. 124,847
In Switzerland February 28, 1936

24 Claims. (Cl. 139—145)

The present invention relates to shuttle picking mechanisms for high speed, high capacity looms, particularly for looms having gripper shuttles, which mechanisms include spring means for supplying the power for their operation.

An object of the present invention resides in the provision of a spring driven shuttle picking mechanism causing rapid acceleration of the shuttle in which not only the shuttle accelerating forces but also the retarding forces are correctly taken care of, predetermined, and limited.

A further object of this invention resides in providing a spring driven shuttle picking mechanism causing rapid acceleration of the shuttle in which shocks and vibrations and wear caused thereby are reduced if not eliminated and long life of the mechanism is assured and by means of which the operating speed of the loom can be increased.

Another object of the present invention is to provide a spring driven shuttle picking mechanism for looms having relatively small gripper shuttles, which mechanism causes rapid acceleration of the shuttle and in which mechanism the surplus energy available in the mechanism after the pick is usefully employed.

A further object of the present invention is to provide a spring driven shuttle picking mechanism causing rapid acceleration of the shuttle, in which mechanism the surplus energy available after the pick is either destroyed without any mechanical shock action or accumulated for further use.

Another object of this invention resides in the provision of a shuttle picking mechanism as set forth in the paragraph next above, the surplus energy of which is transmitted by a liquid and destroyed in a dash pot like means or the surplus energy of which is transmitted by a gaseous medium and destroyed by throttling said medium.

A further object of this invention is the provision of a spring driven shuttle picking mechanism causing rapid acceleration of the shuttle in which surplus energy is destroyed or absorbed by mechanical friction, whereby mechanical shocks and wear are eliminated.

Another object of the present invention resides in providing a spring driven shuttle picking means causing rapid acceleration of the shuttle in which release of the spring is effected by toggle joint means, whereby the mass action of said means serves to reduce the shock caused by the clearance between the shuttle and the picker without reduction of the power stored in the spring for picking the shuttle.

Further and other objects of the present invention will be hereinafter set forth in the accompanying specification and claims and shown in the drawings which, by way of illustration, show what I now consider to be a preferred embodiment of my invention.

In the drawings:

Fig. 1 is a diagrammatic part sectional showing of a mechanism according to the present invention.

Fig. 2 is a diagram showing the pressure of the spring for operating the mechanism according to Fig. 1, the braking forces, and the forces acting on the picker of such mechanism.

Fig. 3 is a diagrammatic part sectional showing of a modified mechanism according to the present invention.

Fig. 4 is a diagram showing the forces which are active in a mechanism according to Fig. 3.

Fig. 5 is a side view of another modification of a mechanism according to the present invention.

Fig. 6 is another view of the mechanism shown in Fig. 5.

Fig. 7 is a diagram showing the forces which are active in a mechanism according to Figs. 5 and 6.

Fig. 8 shows a detail of the mechanism shown in Figs. 5 and 6.

Like parts are designated by like numerals in all figures of the drawings.

In the modification of the present invention according to Figs. 1 and 3, the surplus energy remaining in the picking mechanism after the pick is destroyed.

Referring more particularly to Fig. 1 of the drawings: 1 is the picker which swings about shaft 2 and which is provided with the driving pawl 3. To picker 1, rod 4 is linked by means of stud 5. One end of the picking spring 6 rests on the stationary member 7; the other end of spring 6 rests on plate 8 which is adjustably connected to rod 4. To fulcrum 9 which is rigidly connected with the picking lever 1, piston 11 is connected by means of link 10. Piston 11 is movable within a guide 12 which forms part of a container 13 and which is filled with a liquid, for example, oil. Co-axial with guide 12 is the cylinder 14 in the bottom wall of container 13. Until piston 11 reaches the cavity 14 it produces practically no braking effect, i. e., it is light running or carries out a lost motion. Cylinder 14 is connected for fluid flow with the interior of container 13 by means of channels 15 and 17, the former of which is normally closed by means of spring loaded valve 16. The end part of piston 11 is hollow and open 55

and is provided with a valve 19 for closing the end opening. Valve 19 is normally held in closed position by means of spring 18. It opens when piston 11 moves upwards, i. e., when picker 1 returns to picking position; the interior of container 13 is then connected with the interior of cylinder 14 by means of bores 20.

The lever system consisting of parts 21 and 22, which parts are interconnected by hinge 23, forms a toggle joint. One end of part 21 is linked to a stationary part of the loom, and one end of part 22 is linked to the picker lever 1. In outstretched position, lever 21, 22 holds spring 6 in tensioned position and picker 1 in a position ready to pick. Upon movement of hinge 23 in the direction of arrow 24 by means which do not form part of this invention and are, therefore, not shown, the toggle joint is unlocked and spring 6 released so that picker 1 can swing to the left.

The operation of the mechanism shown in Fig. 1 is as follows:

In the position shown in solid lines, picker 1 is ready to pick shuttle 25. Release of picker 1 is effected by moving hinge 23 in the direction of arrow 24, whereby lever 1 snaps in the direction of arrow 26 under the influence of spring 6. By making hinge 23 heavy, acceleration of picker lever 1 is at first retarded so that its knocking effect on the shuttle 25 is cushioned. According to the present invention, the energy remaining in the picking mechanism after the pick is gradually absorbed and destroyed. For this purpose, a special arrangement is provided which acts during the second part s_2 of the stroke of the picker. s_2 is at least $\frac{1}{4}$ of the total stroke s_3 of the picker. The first part of the stroke of the picker, namely, the part during which the picker moves from position I to position II and acts on shuttle 25 is the working part and is designated 40 by s_1 . During this part of the picker stroke the brake is light running or carries out a lost motion. When the picker has reached position II, piston 11 is in the position shown in dotted lines in Fig. 1 and designated by numeral II, i. e., with its lower end adjacent to the upper opening of cylinder 14. Upon further downward movement of piston 11 into cylinder 14, it must push liquid out of cylinder 14 through valve 16 and channel 17. The movement of piston 11 and the parts 50 connected thereto is thereby retarded. The braking effect during the motion of piston 11 and picker 1 from position II to position III is shown by curve b in Fig. 2. The abscissae of Fig. 2 represent the path of the picking end of picker 1 and the ordinates, in the case of curve b , the braking force, for example, in lbs., in the case of line p , the force exerted by the expanding spring 6 on rod 4, and in the case of dotted curve c , the force effectively acting on picker 1, which 55 force is the difference between the force p and the force b , i. e., $p-b$. When picker 1 is in the position III, plate 8 is in the position shown in dotted lines in Fig. 1. The mechanism for returning picker 1 from position III to position I and for compressing spring 6 is not shown because it is not part of the present invention. At the return movement of picker 1, piston 11 moves upwards, whereby a vacuum is created in cylinder 14, which vacuum causes opening of valve 19 so that liquid can flow from chamber 13 into cylinder 14 through channels 20 in piston 11 and foaming of the liquid in chamber 13 is prevented.

In the embodiment of my invention shown in

Fig. 3 of the drawings, air or a gas is used for braking picker 1. A connecting rod 30 is linked with one end to picking lever 1 by means of stud 5 and with the other end to crosshead 31, whereby by the movement of picker 1 is transmitted to an extension connected with piston 32. A spring 6' is arranged between piston 32 and one end of casing 33.

The device shown in Fig. 3 operates as follows:

The resilient means or spring 6' shown in Fig. 3 is in compressed condition. Upon release of this spring by means not shown, the picking mechanism moves from position I to the left to position II under the influence of a force which is shown in the diagram Fig. 4 by line p' . In Fig. 4, the abscissae indicate the path of the working end of picking lever 1 or the path of piston 32. The ordinates represent forces, for example, lbs. Movement of the mechanism from position I to position II constitutes the working stroke s_1 of the mechanism. Upon movement of piston 32, air is compressed in the braking chamber 34 which is at the left of piston 32 as seen in Figure 3 in the cylinder casing, 33 according to curve b' shown in Fig. 4, and a pressure is exerted on piston 32 which acts counter to the pressure exerted by spring 6'. Between positions I and II, the influence of pressure b' is small. At a movement of piston 32 beyond position II, this counter-pressure becomes noticeable. As soon as piston 32 has reached position III, i. e., has completed the retarding stroke s_2 , compression or braking chamber 34 is connected for air or gas flow with the auxiliary chamber 36 in the rear of the piston by means of the braking pressure control means consisting, in the embodiment of the present invention shown in Fig. 3, of recesses or cavities 37 provided in the interior wall of casing 33, whereby the compressed air or gas expands into auxiliary chamber 36 and the energy accumulated in the air or gas is destroyed. In case the braking force exerted on the mechanism when it reaches position III is not sufficient to bring it to a standstill, upon further movement of piston 32 to the left to position IV, an additional air cushion is built up which finally stops the mechanism. s_3 indicates the total normal stroke of the picking mechanism. Return movement of piston 32 and picker lever 1 may be effected by any known mechanism, for example, as shown in my co-pending application Ser. No. 90,962. In the position ready for the pick, which position is designated by numeral I in Fig. 3, chambers 34 and 36 are interconnected for air or gas flow by means of braking chamber or casing filling means which consist, in the embodiment of the present invention shown in Fig. 3, of recesses or cavities 38 provided in the interior wall of casing 33. In order to further control the contents of chamber 36, a channel or conduit 40 is provided which connects chamber 36 with the outside. It terminates with its inner end in the sliding surface for the extension of piston 32 which extension terminates in the crosshead 31 and flow of air or gas through conduit 40 is controlled by the movements of said crosshead. Upon inward movement of the latter, channel 40 at first remains open, whereby inflow of air and start of the working stroke is facilitated. At furthest movement to the left of crosshead 31, the mouth of channel 40 is closed and a vacuum created in chamber 36, whereby the movement of the picking mechanism is retarded.

Figures 5 to 8 show a third modification of the

present invention. Picking lever 1 is keyed to one end of a torsion spring 41; the other end of this spring is rigidly connected with a stationary member 42. One end of a connecting rod 44 is linked to lever 1 by means of stud 43. The other end of connecting rod 44 is revolvably connected with crank 45 of shaft 46. Two brake members 50 and 51 are individually revolvably connected to stationary studs 48 and 49, respectively. These 5 brake members are individually pressed to the crank disc 54 by means of springs 52 and 53, respectively. Brake members 50 and 51 are so shaped that turning of crank shaft 46 is possible in the direction of arrow 55 and prevented in the opposite direction. To shaft 46, another shaft 46' 10 is coaxially connected by means of a claw coupling 56. Shaft 46', which may be driven by means of a chain wheel 57, is provided with a claw 58 which cooperates with a claw 59 which is connected to shaft 46 and causes revolution of the latter shaft 15 in the direction of arrow 60. These details are shown in Fig. 8.

The operation of the picker mechanism shown in Figs. 5 to 8 is as follows:

25 The position in which picker 1 is shown in Fig. 6 is its rest position. In order to increase the tension of spring 41, picker 1 is moved by means of crank 45 into the position designated by Roman I in Fig. 6. In the position of the picker 30 shown in solid lines in Fig. 6, claw 58 abuts against claw 59 so that shaft 46' moves shaft 46 and picker 1 immediately when wheel 57 is revolved. In position I of picker 1, connecting rod 44 is just a little beyond its right dead center position. 35 The tension of spring 41 increases as shown in the diagram Fig. 7, in which the abscissae indicate the stroke *s* of picker 1 and the ordinates of line *b* the tension *p* of spring 41, for example, in lbs. After passing the right dead center position, i. e., 40 position I of rod 44, picker 1 snaps to the left, first into position II, in which position the tension of spring 41 is zero, and under the influence of inertia forces into position III, whereby spring 41 is again twisted and its tension increased. 45 This tension and the inertia forces still remaining in the crank system return picker 1 from position III into the position shown in solid lines in Fig. 6 so that the kinetic energy of the picker mechanism, with the exception of the energy lost 50 by friction, is again accumulated in spring 41 in the form of potential energy. If crank 45 tends to change its direction of rotation, this is prevented by the locking means 50 and 51 so that the energy remaining in the mechanism after the 55 pick is caught in such manner that it can be used for the next following working stroke and undesired vibrations of the picker are prevented. The picking mechanism remains blocked in the position shown in solid lines in Fig. 6 until claw 60 58 again pushes claw 59 and the tension of spring 41 is increased for the next following pick.

While I believe the above described embodiments of my invention to be preferred embodiments, I wish it to be understood that I do not 65 desire to be limited to the exact details of design and construction shown and described, for obvious modifications will occur to a person skilled in the art.

What I claim is:

70 1. A shuttle picking mechanism for high speed, high capacity looms for weaving comprising a picker, operating means connected thereto and adapted to periodically operate said picker for picking the shuttles across the loom, brake means connected with said picker, said brake means

comprising an operating medium, a cylinder, a piston adapted to operate in said cylinder, pressure control means connected with said cylinder for controlling the pressure of the operating medium in said cylinder, cylinder filling means which refill said cylinder with operating medium immediately after completion of the braking stroke of said piston and which operate independently from said pressure control means. 5

2. A shuttle picking mechanism for high speed, 10 high capacity looms for weaving comprising a picker, operating means connected thereto and adapted to periodically operate said picker for picking the shuttle across the loom, brake means connected with said picker, said brake means comprising an operating medium, a cylinder, a piston adapted to operate in said cylinder, pressure control means connected with said cylinder for controlling the pressure of the operating medium in said cylinder, cylinder filling means connected 15 with said piston which refill said cylinder with operating medium immediately after completion 20 of the braking stroke of said piston and which operate independently from said pressure control means. 25

3. A shuttle picking mechanism for high speed, high capacity looms for weaving comprising a picker, operating means connected thereto and adapted to periodically operate said picker for picking the shuttle across the loom, brake means 30 connected with said picker, said brake means comprising an operating medium, a cylinder, a piston adapted to operate in said cylinder, pressure control means connected with said cylinder for controlling the pressure of the operating medium in 35 said cylinder, cylinder filling means which refill said cylinder with operating medium immediately after completion of the braking stroke of said piston and which operate independently from said pressure control means, a container containing 40 said operating medium, said cylinder, piston, pressure control and filling means all being located within said container and immersed in said operating medium.

4. A shuttle picking mechanism for high speed, 45 high capacity looms for weaving comprising a picker, operating means connected thereto and adapted to periodically operate said picker for picking the shuttle across the loom, brake means 50 connected with said picker, said brake means comprising an operating medium, a cylinder, a piston adapted to operate in said cylinder, pressure control means connected with said cylinder for controlling the pressure of the operating 55 medium in said cylinder, cylinder filling means which refill said cylinder with operating medium immediately after completion of the braking stroke of said piston and which operate independently from said pressure control means, a container containing said operating medium and 60 having a bottom part which comprises said cylinder, said piston, pressure control and filling means all being located within said container and immersed in said operating medium. 65

5. A shuttle picking mechanism for high speed, high capacity looms for weaving comprising a picker, operating means connected thereto and adapted to periodically operate said picker for picking the shuttle across the loom, brake means 70 connected with said picker, said brake means comprising an operating medium, a cylinder, a piston adapted to operate in said cylinder, pressure control means connected with said cylinder for controlling the pressure of the operating medium in 75

said cylinder, cylinder filling means which refill said cylinder with operating medium immediately after completion of the braking stroke of said piston and which operate independently from said pressure control means, a container containing said operating medium, said cylinder being located within said container, and guide means with which said piston is movably connected for guiding said piston in a lost motion through said container until it reaches said cylinder.

6. A shuttle picking mechanism for high speed, high capacity looms for weaving comprising a picker, operating means connected thereto and adapted to periodically operate said picker for picking the shuttle across the loom, brake means connected with said picker, said brake means comprising a container containing an operating medium and having a bottom part with a cylinder built in, and a piston adapted to operate in said cylinder.

7. A shuttle picking mechanism for high speed, high capacity looms for weaving comprising a picker, operating means connected thereto and adapted to periodically operate said picker for picking the shuttle across the loom, brake means connected with said picker, said brake means comprising a container containing an operating medium and having a bottom part with a cylinder built in, a piston adapted to operate in said cylinder, and a guide means movably cooperating with said piston and being connected with said container for guiding said piston in a lost motion until it reaches said cylinder.

8. A shuttle picking mechanism for high speed, high capacity looms for weaving comprising a picker, operating means connected thereto and adapted to periodically operate said picker for picking the shuttle across the loom, hydraulic brake means connected with said picker and comprising a cylinder and a piston movable therein, brake force control means which control means make said brake means substantially ineffective during the first part of the picking stroke of said picker, throttling and filling means operating independently of one another and of said brake force control means.

9. A shuttle picking mechanism for high speed, high capacity looms for weaving comprising a picker, operating means connected thereto for periodically operating said picker and picking the shuttle across the loom, brake means operatively connected with said picker and comprising a cylinder and a piston moving therein, operating medium outlet control means connected with said cylinder for controlling the escape of operating medium from said cylinder, and cylinder filling means for filling said cylinder with operating medium, said outlet control means and said filling means operating completely independently of one another.

10. A shuttle picking mechanism for high speed, high capacity looms for weaving comprising a picker, operating means connected thereto for periodically operating said picker and picking the shuttle across the loom, brake means operatively connected with said picker and comprising a cylinder and a piston moving therein, operating medium outlet control means connected with said cylinder for controlling the escape of operating medium from said cylinder, and supply means for unobstructed supply of operating medium to said cylinder, said supply means being controlled by said piston and separated thereby from the pressure side of said piston during the entire braking stroke of said piston.

11. A shuttle picking mechanism for high speed, high capacity looms for weaving comprising a picker, operating means connected thereto for periodically operating said picker and picking the shuttle across the loom, brake means operatively connected with said picker and comprising a cylinder and a piston moving therein, operating medium outlet control means connected with said cylinder for controlling the escape of operating medium from said cylinder, cylinder filling means for filling said cylinder with operating medium, said outlet control means and said filling means operating completely independently of one another, and brake force control means which are controlled by said piston and nullify the brake force during the first part of the picking stroke of said picker.

12. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a casing and a piston movable therein, medium pressure control means and casing filling means connected with said casing and operating completely independent from one another with respect to the effect on the pressure of the medium in said cylinder.

13. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a cylinder and a piston movable therein, medium pressure control means and cylinder filling means connected with said cylinder and being operated through the movement of said piston and operating completely independent from one another with respect to the effect on the pressure of the medium in said cylinder.

14. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a casing and a piston movable therein, medium pressure control means and casing filling means connected with said casing and being operated through the movement of said piston, said casing filling means being ineffective during the braking stroke of said piston.

15. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a cylinder and a piston movable therein, medium pressure control means and cylinder filling means connected with said cylinder and being

operated through the movement of said piston, said medium pressure control means and said cylinder filling means being ineffective during a substantial part of the braking stroke of said piston.

5 16. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a casing and a piston movable therein, medium pressure control means and casing filling means connected with said casing and being operated through the movement of said piston, said medium pressure control means and said casing filling means operating consecutively and independently from one another with respect to the effect on the pressure of the medium in said casing.

10 17. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a cylinder and a piston movable therein, medium pressure control means and cylinder filling means connected with said cylinder and being operated through the movement of said piston, said medium pressure control means and said cylinder filling means being ineffective during a substantial part of the braking stroke of said piston and operating independently from one another with respect to the effect on the pressure of the medium in said cylinder.

15 18. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including, in combination, a casing, a piston movable in said casing and dividing said casing into a braking chamber and an auxiliary chamber, and piston controlled braking chamber filling means interconnecting both said chambers at a predetermined position of said piston.

20 19. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a cylinder, a piston movable in said cylinder and dividing said cylinder into a braking chamber and an auxiliary chamber, and a plurality of independently piston controlled braking pressure control means connected with said cylinder and interconnecting both said chambers at predetermined positions of said piston.

25 20. A shuttle picking mechanism for high speed, high capacity looms for weaving comprising a picker, operating means connected thereto and adapted to periodically operate said picker for picking the shuttle across the loom, brake means adapted to be operated by a gaseous me-

dium and being operatively connected with said picker, said brake means including in combination a casing, a piston movable in said casing and dividing said casing into a braking chamber and an auxiliary chamber, piston controlled braking chamber filling means interconnecting both said chambers at a predetermined position of said piston.

5 21. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a casing having a braking end which is completely closed and an auxiliary end which is also closed and provided with a conduit for medium flow into and from said casing, a piston movable in said casing and dividing said casing into a braking chamber and an auxiliary chamber, an extension connected with said piston and extending through said auxiliary chamber and controlling medium flow through said conduit, and piston controlled braking pressure control means connected with said casing and interconnecting both said chambers at predetermined positions of said piston.

10 22. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a cylinder, a piston movable in said cylinder and dividing said cylinder into a braking chamber and an auxiliary chamber, a plurality of independently piston controlled braking pressure control means connected with said cylinder and interconnecting both said chambers at predetermined positions of said piston, and resilient means situated in said auxiliary chamber and being connected with said piston and said cylinder for counteracting the medium pressure in said braking chamber.

15 23. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including, in combination, a casing, a piston movable in said casing and dividing said casing into a braking chamber and an auxiliary chamber, piston controlled braking chamber filling means interconnecting both said chambers at a predetermined position of said piston in said auxiliary chamber and being connected with said piston and said casing for actuating said piston.

20 24. A shuttle picking mechanism for high speed, high capacity looms for weaving comprising a picker, operating means connected thereto and adapted to periodically operate said picker for picking the shuttle across the loom, brake means adapted to be operated by a gaseous medium and being operatively connected with said picker, said brake means including in combination a casing having a braking end which is

completely closed and an auxiliary end which is also closed and provided with a conduit for medium flow into and from said casing, a piston movable in said casing and dividing said casing into a braking chamber and an auxiliary chamber, an extension connected with said piston and extending through said auxiliary chamber and controlling medium flow through said conduit, piston controlled braking pressure control

means connected with said casing and interconnecting both said chambers at predetermined positions of said piston, and resilient means situated in said auxiliary chamber and around said extension and being connected with said piston and said casing for counteracting the medium pressure in said braking chamber.

ALBERT MOESSINGER.
